[57] CLAIM

The ornamental design for a battery for a portable communication device, as shown and described.

DESCRIPTION

FIG. 1 is a top plan view of a battery showing our new design;

FIG. 2 is a bottom plan view thereof;

FIG. 3 is a right side elevational view thereof;

FIG. 4 is a left side elevational view thereof;

FIG. 5 is a back elevational view thereof;

FIG. 6 is a front elevational view thereof;

FIG. 7 is a top and upper left isometric view thereof;

FIG. 8 is a rear and lower right isometric view;

FIG. 9 is a top plan view of a second embodiment of the battery;

FIG. 10 is a bottom plan view thereof;

FIG. 11 is a right side elevational view thereof;

FIG. 12 is a left side elevational view thereof;

FIG. 13 is a back elevational view thereof;

FIG. 14 is a front elevational view thereof;

FIG. 15 is a top and upper left isometric view thereof; and,

FIG. 16 is a rear and lower right isometric view.
